UNITED STATES PATENT OFFICE

JOSEPH E. BOND, OF APPLETON, WISCONSIN

AGITATOR

Application filed March 5, 1928. Serial No. 259,092.

My invention relates to the art of paper making and particularly to means for agitating paper pulp.

In the development of the art it has been found possible to greatly increase the capacity of a given equipment by increasing the density (or, in other words, lessening the fluidity) of the pulp during its treatment preceding delivery to the Fourdriniers. While in 10 the old practice a 2½% pulp was considered proper and of the maximum density possible, it is now common to deal with 6% solutions, with correspondingly increased production capacity.

15 However, many difficult problems are encountered in handling pulp of this density due to its lack of fluidity and its tendency to mass or cake in the storage or treatment tanks and containers. This tendency is inherent in 20 the nature of the material under treatment due to its fibrous character and to the physical law of attraction of solids. The liquid within which the solids are carried serves merely as a supporting medium therefor and facilitates rather than hinders the massing and intertwining of the fibers.

To avoid massing and stratifying of the pulp in the liquid and to maintain a uniform density throughout the entire body of material it must be kept in motion and the motion producing means should have a tendency to break up and tear apart any large or small masses of pulp. In the old practice the mixture was kept in motion by means of paddles 35 or impellers in the tank, but this apparatus had very little tendency to break up masses of pulp, and was wholly ineffective with stock of increased density. Furthermore, such apparatus required an outlay of power 40 not commensurate with the results secured.

The tanks, chests or containers which are in place and must be utilized for the new plan of operation are of many and varied forms, all of great size, some narrow and of great 45 length, some deep and some round. The problem has been, therefore, to provide means applicable to these various forms of tanks that would insure effective circulation, the breaking up of pulp masses and the main- 50 tenance at all times of a proper consistency

throughout the whole volume of material, with a minimum of power expenditure.

My invention will be more readily understood by reference to the accompanying drawings, of which—

55 Fig. 1 is a transverse sectional view through an agitator constructed in accordance with my invention, the view being taken on the line 1—1 of Fig. 3;

Fig. 2 is a vertical sectional view, and

60 Fig. 3 is a transverse sectional view on the line 3—3 of Fig. 2.

In the drawings I have illustrated a cylindrical horizontally disposed tank having cylindrical wall 10 and end walls 11, 12. 65 Mounted within the tank and extending vertically thereof is a baffle wall 13 which abuts the end wall 11 and terminates short of the end wall 12 in a continuous vertical deflector 14. The baffle wall is laterally stiffened or braced by means of the struts 15 extending horizontally at the horizontal center line 70 of the tank.

A pump 16 is mounted in the end wall 11, being operated by a motor 17. The inlet pipe 75 18 for the pump receives material at a low level in the tank from a compartment at one side of the said baffle and the discharge pipe 19 projects upwardly from the pump, thence through the baffle wall 13 and dis- 80 charges into the chamber on the opposite side of said baffle.

The tank is of relatively great length and adapted to contain a large quantity of paper stock. The pump being in operation, the ma- 85 terial is drawn into the inlet and from the pump is discharged through an outlet to an adjacent compartment at a higher level. It thence travels rearwardly around the deflector 14 and backwardly toward the pump. 90 By this means the material is suitably agitated and kept in motion at all times.

I claim:

1. In combination, a cylindrical, horizontally disposed tank having a transverse baffle 95 extending longitudinally within the same and terminating short of one end of the tank, a deflector at the end of said baffle, and a pump at the opposite end of said tank, said pump having an inlet near the lower level at one 100

side of said baffle and an outlet at a higher level on the other side of said baffle.

5 2. In combination, a cylindrical horizontally disposed tank having a transverse vertical longitudinally extending baffle wall connected to the front end wall and terminating short of the rear end wall of the tank, a pump having its inlet at a low point at one side of said baffle wall and its outlet at a higher point at the other side of said baffle wall.

10 3. In combination, a cylindrical, horizontally disposed tank having a transverse vertical longitudinally extending baffle wall connected to the front end wall and terminating short of the rear end wall of the tank, a pump projecting through the front end wall of the tank having its inlet at a low point at one side of said baffle wall and its outlet at a higher point at the other side of

15 said baffle wall.

20 In testimony whereof I have affixed my signature.

JOSEPH E. BOND.
